(57) **CLAIM**

The ornamental design for a front bezel for computer enclosure, as shown and described.

DESCRIPTION

FIG. 1 is a perspective view of a front bezel for computer enclosure showing a first embodiment of our new design mounted on a computer enclosure;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof in a using condition;

FIG. 9 is a rear elevational view of the front bezel of FIG. 1;

FIG. 10 is a perspective view of a front bezel for computer enclosure showing a second embodiment of our new design mounted on a computer enclosure;

FIG. 11 is a front elevational view of the second embodiment thereof;

FIG. 12 is a rear elevational view of the second embodiment thereof;

FIG. 13 is a left side elevational view of the second embodiment thereof;

FIG. 14 is a right side elevational view of the second embodiment thereof;

FIG. 15 is a top plan view of the second embodiment thereof;

FIG. 16 is a bottom plan view of the second embodiment thereof;

FIG. 17 is a perspective view of the second embodiment thereof in a using condition; and,

FIG. 18 is a rear elevational view of the front bezel of FIG. 10.

The broken line showing of a computer enclosure in the views is for illustrative environmental purposes only and forms no part of the claimed design.
